UNITED STATES PATENT OFFICE.

ALBERT DAVID LEWIS, OF ATLANTA, GEORGIA.

DESIGN FOR A BOTTLE OR SIMILAR ARTICLE.

Application filed March 9, 1926. Serial No. 16,850. Term of patent 14 years.

To all whom it may concern:

Be it known that I, ALBERT D. LEWIS, a citizen of the United States, residing at Atlanta, in the county of Fulton and State of Georgia, have invented a new, original, and ornamental Design for a Bottle or Similar Article, of which the following is a specification, reference being had to the accompanying drawing, forming part thereof.

The figure is a side elevation of a bottle, showing my new design.

I claim:

The ornamental design for a bottle or similar article, as shown.

In testimony that I claim the foregoing as my own, I have hereto affixed my signature.

ALBERT DAVID LEWIS.
